DRAFT-TUBE FOR HYDRAULIC TURBINES.

1,199,207.

Specification of Letters Patent. Patented Sept. 26, 1916.

Application filed September 1, 1914. Serial No. 859,653.

To all whom it may concern:

Be it known that we, FRED B. RYONS and MARK A. REPLEGLE, citizens of the United States, and residing, respectively, at Lincoln, Nebraska, and Akron, Ohio, have jointly invented the Improvements in Draft-Tubes for Hydraulic Turbines as herein described.

This invention relates to the construction, 10 equipment and operation of draft tubes for hydraulic turbines.

The objects of the invention are to provide for increasing the speed and power of water turbines operating under a given 15 head, to reduce the size of turbine needed to deliver a given amount of power under a given head, to furnish means for varying the speed and power of the turbine, to prevent diminution of speed or power due to 20 fall or loss of head during high water or flood times, and to provide for utilizing surplus water at any time to increase the speed and power of such turbines.

The accompanying drawing shows a construction sufficiently clear to enable others to make and use our device.

Before referring in detail to the drawing, it may be noted it is known in the present state of the art that to economically get energy by turbine from a descending column of water, the water should descend through a closed conduit or pipe whose function is to produce a very rapid motion at some narrowed portion or throat thereof; and that the turbine should be located so that its ports are in effect above the throat, but its passage vents in the aggregate actually constitute said throat or an integral portion of it. Designating the water actually passed 30 through the turbine as the primal column, we accelerate this primal column by a draft tube which is arranged as an extension of the turbine discharge pipe; and further accelerate it, when desired, by an auxiliary 35 column which also accelerates itself by utilizing part of the identical throat which is designed to accelerate the primal column when the auxiliary column is excluded. We have discovered that in order to get the best 40 effect of the auxiliary column, the throat of the primal column should be extended to a point where the auxiliary column may be united with it at the maximum accelerated speed of the combined columns, and that the 45 auxiliary column should be moving in the same direction as well as at the same speed,

at the time of merging with, and at point of junction with said primal column.

The function of our device now having been set forth, it may be more fully explained by reference to the drawing in which—

Figure 1 is a view mostly in vertical section, of a forebay with turbine installation embodying our accelerator. Fig. 2 is an under side view of the main features of such installation. Fig. 3 is a view at right angles of part of control mechanism shown in Fig. 1.

Referring to the views, 1 denotes a vertical turbine within a penstock 18 having ports 1' controlled by a pinion 17 carried by a shaft 16 and hand wheel 6'. The turbine is supported by I beams 15, 15, and has a curved discharge pipe 2 over the lower end 75 of which fits the sliding gate 3. This gate is a cylindrical ring having toothed rack arms 4, 4 secured to it at 4', 4', pinions 5, 5 engaging with said arms and said pinions being arranged to be driven 80 by the shaft 7 carrying the chain sprocket 8 connecting with sprocket 8 on shaft 7 carrying the hand wheel 6, all supported by hangers bolted to the floor 14 as shown in Fig. 3.

An infuser 9 which may be constructed as a single casting is set solidly in the wall 12 of the penstock 18, its flaring mouth 9' concentrically encircling the sliding ring gate 3. The infuser and ring gate must be kept 90 in axial alinement and a pier 13 to which the discharge pipe 2 is anchored serves this purpose. To the flange 10 of the infuser a flaring draft tube 11 connects making continuous inner walls. The diameter of the 95 draft tube at the flange 10 corresponds closely with the throat diameter 9" of the infuser, and also with the diameter of the discharge pipe 2; but it should increase in diameter outward at a rate equal to about 100 one sixteenth part of the throat diameter to each foot of length, the length being indefinite or limited to conditions at point of installation. In the larger installations the draft tube 11 will for the most part be constructed of concrete or masonry, but is here shown as of metal. It is intended to represent the infuser as leading through the wall of the penstock 18 which supplies water to the turbine and infuser from a common 110 head or upper level as 19 at low water and 20 at high water; and it is to be understood

the farther end of draft tube as well as the infuser is at all times to be submerged under low tail water indicated by the level 19'.

In the operation of the device at low water, the ring gate 3 is to be set in the closed position, its rim 3' impinging on the concave surface of the infuser throat 9" in the vicinity of the dotted line. In this position the draft tube performs the usual function only. In case of excess of water such as would tend to raise the level of the water in the penstock, say from level 19 to level 20 and the level below spillway from 19' to 20', the apparent head or difference between levels of head water and tail water, would be materially decreased. Under the latter conditions the ring gate 3 is to be slid back, by means of the hand wheel, allowing an annular opening between its rim 3' and the concave surface of the infuser throat 9" through which opening an annular auxiliary stream is inducted to give greater velocity to the outgoing water in the draft tube 11. The result of this is to remove part of the atmospheric pressure from the lower end of the discharge pipe 2, and therefore to accelerate the discharge and flow through the turbine and increase its power. While of course not all of the energy of the inducted stream is effective in the turbine, yet so great a volume may be thus inducted, if need be, that the power of the turbine may be brought to double or treble what it would be without this auxiliary.

We are aware that auxiliary streams have been inducted into turbine draft tubes heretofore, for this purpose, but the induction has been effected at points beyond, and in effect below the throat, instead of in, and in effect above the throat of the main conduit as we do it. Our infuser constitutes an auxiliary conduit having a throat formed by its inner surface and the rim of the ring gate, within the throat of the main conduit, in effect, so that the primal column of water and the auxiliary column of water meet at the place of greatest velocity of the combined columns; it being understood that the discharge pipe 2 is essentially a prolonged throat, and may be in straight axial alignment with the turbine or curved as shown, provision always being made for room and connections to operate the ring gate 3.

Having thus described the invention and operation thereof, what we claim and desire to secure by Letters Patent is:

1. The combination with a hydraulic turbine, of a discharge pipe of substantially uniform diameter reaching below the low level of tail water, an extension sleeve slidably connected to the outer end of said discharge pipe, means for sliding said sleeve longitudinally of the pipe, an expanding draft tube having its smaller end of a diameter substantially equal to that of the

discharge pipe aforesaid, arranged in axial alignment of said discharge pipe, and having a funnel shaped infuser extending from its smaller end which surrounds said sliding sleeve, and said sleeve being adapted to close the gap between the discharge pipe and the draft tube aforesaid, by impingement on the inner surface of the narrowest diameter of the infuser aforesaid.

2. A hydraulic accelerator for turbines comprising a penstock containing the turbine, a discharge pipe of uniform diameter attached to the turbine and reaching below the low level of tail water, a slideable gate or sleeve on the end of said pipe, means for moving said sleeve longitudinally of the pipe, an expanding draft tube leading from the penstock and having a neck of a diameter substantially equal to that of the pipe, a funnel-shaped infuser in the penstock wall, secured to said neck and arranged in axial alignment with and concentrically surrounding the outer end of said sleeve, and said sleeve adapted to impinge on the inner surface of the infuser at its narrowest part for the purpose set forth.

3. In combination with a penstock of a turbine draft tube leading therefrom and having a narrowed neck or throat located below the level of tail water, of an infuser in the penstock wall constituting part of said throat, a flaring rim of the infuser within the penstock adapted to induct water from the penstock into the draft tube, a discharge pipe leading from the turbine and having a diameter substantially equal to that of said throat, and arranged to discharge water into said infuser coincidentally with that inducted from the penstock for the purpose set forth.

4. The herein described accelerator for water turbines, comprising a penstock, a discharge pipe of the turbine leading outward of the penstock, an expanding draft-tube having a throat of equal diameter to that of the discharge pipe located in the wall of the penstock and below the level of tail water but arranged in axial alignment with the discharge pipe at a distance in advance leaving a gap between, a sliding gate or sleeve on the end of said discharge pipe, said sleeve adapted to engage with the inner surface of the throat aforesaid, and means for moving said sleeve longitudinally of the pipe to open and close said gap.

5. The combination with a turbine draft-tube adapted to carry discharge water and auxiliary water and having a throat or narrow neck therein, of a discharge pipe having a diameter substantially equal to said neck leading from the turbine into said neck, and an infuser arranged concentric of the discharge end of said pipe adapted to induct auxiliary water into said draft tube

at said throat and below the level of tail water, the walls of said draft-tube expanding outward down stream from the throat at a gradual increase in diameter.

- 5 6. The combination with a hydraulic turbine, of a discharge pipe extending below the level of tail water, an expanding draft-tube having a neck of a diameter substantially equal to that of the discharge pipe,
10 and a funnel-shaped infuser extending from said neck, in axial alinement with the end of said discharge pipe, and surrounding the end thereof for the purpose set forth.

7. The combination with a hydraulic turbine of a discharge pipe of uniform di-

ameter, an expanding draft tube having a neck, and a funnel-shaped infuser extending from said neck substantially in axial alinement with the end of the discharge pipe and surrounding said end, for the purpose set forth. 20
